CHARLES BEERS, OF NEW HAVEN, CONNECTICUT, ASSIGNOR, BY MESNE ASSIGNMENTS,
TO THE INTERNATIONAL BREAD WRAPPING MACHINE COMPANY, A CORPORATION
OF MAINE.

WRAPPING-MACHINE.

1,194,350.

Specification of Letters Patent. Patented Aug. 15, 1916.

Application filed June 28, 1911. Serial No. 635,789.

To all whom it may concern:

Be it known that I, CHARLES BEERS, citizen of the United States, residing at New Haven, in the county of New Haven and 5 State of Connecticut, have invented certain new and useful Improvements in Wrapping-Machines; and I do hereby declare the following to be a full, clear, and exact description of the invention, such as will 10 enable others skilled in the art to which it appertains to make and use the same.

My invention relates to wrapping machines adapted for automatically effecting the initial wrap of paper about various articles, and particularly such articles as vary 15 in size, like, for instance, a loaf of bread. In automatically wrapping articles of uniform size, the wrapper sections can be cut of uniform length; but with articles that 20 vary in size, the paper wrapper must of necessity vary with each individual article. To provide for this, it is necessary that the first step in wrapping articles of varying sizes is for each article to determine the 25 amount of paper required to completely envelop it without leaving any projecting ends.

Therefore, the object of my invention is to automatically cause each article to draw off from a reel or other like source of supply, 30 the amount of paper necessary to form a wrapper for the article preparatory to the folding operation, such article being represented in the several views as a loaf of bread.

35 Referring to the drawings wherein the same figures and letters of reference indicate like parts throughout the several views: Figure 1 represents a side elevation of the machine and sectional view of the driving shaft looking in the direction of arrows *a* and *b* of Figs. 2 and 3; Fig. 2 is a rear elevation looking in the direction of arrow *c* of Fig. 1; Fig. 3 is a front elevation looking in the direction of arrow *d* of Fig. 1; 40 Fig. 4 is an end elevation partly in section of the feeding drum looking in the direction of arrow *e* of Fig. 5; Fig. 5 is a side elevation of the feeding drum, broken view of its shaft and cam supporting brackets; Fig. 45 50 6 is a sectional end elevation of the feeding drum on line 6 of Fig. 5; Fig. 7 is a longi-

tudinal sectional view of the feeding drum on line 7 of Fig. 4; Fig. 8 is a detail upper plan view of the paper cutting knife and broken view of its supporting frame and connecting rod; Fig. 9 is a detail side elevation of the knife gate, sectional view of its supporting frame, and broken view partly in section of the gate actuating lever; Fig. 10 is a detail sectional end view of the knife 60 and gate on line 10 of Fig. 8; also broken view of the gate support and gate connecting rod; Fig. 11 is a perspective detail view of a loaf of bread and its wrapper; Fig. 12 is a broken end diagram of the loaf feeding 65 drum and paper reel, broken view of several of the endless loaf carriers showing the position of the carriers, drum and knife when a wrapper is about to be severed; Fig. 13 is a detail view of the intermittent mechanism for timing the travel of the loaf carriers and sectional view of their supporting shafts; and Figs. 14, 15 and 16 are detail views of the loaf carriers.

The shafts carrying the several rotative 75 elements are journaled in the side frames 1 and 2 of the machine.

3 is the main driving shaft and 4 the driving pulley.

5 and 6 are shafts each of which carries a 80 pair of sprocket wheels, viz. 7, 8, 9 and 10, having the notches 11 spaced equally about their periphery to receive the loaf carrier supporting rods or tubes 12. The loaf carriers are formed in two sections journaled 85 on the rods 12. One section comprises the loaf supporting arms 13, Figs. 14 and 15, having the right angle arms 13^a and face plate 13^b integral therewith. The other Z-shaped section comprises the arms 14 also 90 journaled on the rods 12 and having the arms 14^a and face plate 14^b integral therewith.

15 are the loaf retaining spring fingers carried by the arms 14 and having at their 95 ends the small rods 16 adapted to engage the paper and loaf when the latter is delivered onto the arms 13 in the manner presently to be more fully described.

17, Figs. 2 and 3, is a pinion on the driving shaft meshing with the pinion 18 on the intermittent shaft 19 whose outer end car-

ries a part of the intermittent mechanism comprising the disk 20 and pins or rolls 21, eccentrically located with respect to the shaft, and diametrically situated with respect to each other.

The second intermittent shaft 22 carries on one of its outer ends the disk 23 (see also Fig. 13) having the six equidistant notches 24 in its periphery adapted to be alternately engaged by the pins 21 of the disk 20. The opposite end of shaft 22 carries the large gear 25 meshing with the pinion 26 on the lower sprocket wheel shaft 6. By the arrangement of the gearing and intermittent mechanism above described, the disk 23 will make one-sixth of a revolution; the sprocket shafts 5 and 6, one-third of a revolution to one revolution of the driving shaft, thus timing the travel of the loaf carriers with respect to the travel of the loaf feeding mechanism about to be described.

The loaf feeding mechanism comprises the drum 27 mounted on the shaft 28 journaled in the machine frame.

25 29, 29^a, 30, 30^a, 31 and 31^a, Figs. 4, 5, 6 and 7, are levers that serve the purpose of loaf feeders during a part of the revolution of the drum. These levers are pivotally supported on the bolts 32 and operate against 30 the inside faces of the heads 27^a of the drum. The free ends of these levers carry the rolls 33 adapted to travel in the curved radial slots 34 formed in the before mentioned drum heads.

35 35 and 36 are stationary cam plates in close proximity to the drum heads and outside of the same and are secured to the brackets 37 and 38, which brackets are supported on the machine frame.

40 39 and 40, Figs. 1, 4 and 5, are curved plates also secured to the before mentioned brackets so that the space between said curved plates and the cam plates 35 and 36 will form cam grooves for the rolls carried 45 by the loaf feeding levers for the purpose of withdrawing said levers within the outer surface of the drum. While the rolls of these levers are engaged with the outer curved edges of the cam plates, the bars 41, 0 which bars connect each opposed pair of levers, project beyond the periphery of the drum and close to the loaf supporting platforms 42, and when the rolls of any of the pairs of levers contact with the plates 39 and 40 they will be carried down between the plates 35, 36, 39 and 40 and cause the opposed levers with their connecting bar to retreat into the position shown by the lever 31^a, Fig. 6, and remain in such position 55 until the rotation of the drum has brought the roll of such lever or levers in contact with the cam plates 35 and 36 when they are again forced outward.

60 43 are outwardly projecting rods in the 65 ends of the bars 41, which rods are adapted

to drop into the notches 44 in the heads of the drum when the levers are withdrawn to limit the inward movement of said levers.

The knife mechanism is supported on the bracket 45, Fig. 1, and it comprises the gate 70 46 (see also Figs. 8, 9 and 10) operatively mounted in the ways 47 of the bracket.

48 is the knife carried by the gate, and 75 49 is a lever pivotally supported on the bracket whose inner end is operatively connected to the gate, and its outer end with the connecting rod 50. The opposite end of this rod is connected to the trip lever 51, Fig. 1, so that, when the cam 52, on the driving shaft, actuates said trip lever, the 80 knife will be moved inward to cut a wrapper section, presently to be described.

Motion is communicated from the upper sprocket wheel shaft 5 to the drum shaft 28 through the medium of the gear 53 on shaft 85 5 meshing with the gear 54 on the short shaft 55, Fig. 1. Said shaft 55 carrying the sprocket wheel 56 which wheel is connected to the sprocket wheel 57 on shaft 28 through the medium of the chain 58.

59, Fig. 1, is a roll of paper whose shaft 60 is removably journaled in the upper extension of the machine frame. From this roll the paper A is drawn off and passed over the roller 61 and carried from thence 90 down in front of the feeding drum 27 and between said drum and the vertical faces of the loaf carriers 13 and 14. The loaves B are fed along the platforms 62, either mechanically or by hand, and the inner one of 100 said loaves is deposited on to one of the drum platforms 42 and under the control of one of the projecting feeding levers. Assuming the machine to have just started with the feeding drum empty with the exception of a single loaf, B', just pushed onto the drum as above described. Then the paper will lie in front of the feeding drum as shown at Fig. 12 until the loaf B' is 105 brought into contact therewith by the rotation of said drum. To avoid confusion this second position of the loaf will be indicated as B^a. In Fig. 12 this contact or engagement of the loaf with the paper is represented as just taking place. The rotation 110 of the drum will force the loaf against the inclined portion A¹ of the paper strip, as shown by the third position, viz., B^b, Fig. 1, and draw off from the roll 59 the required amount of paper when said loaf has been 115 deposited on one of the loaf carriers whose rotary travel has been so timed with respect to the rotary travel of the feeding drum that it will have reached the proper position to receive the loaf at the proper time. While the arms 13 of the loaf carrier are moving downward into position to receive the loaf in contact with the paper strip; the spring fingers 15 of the arms 14 will also be brought in contact with the 120 125 130

paper and force it against the loaf and hold said loaf firmly in position against the arms 13. As soon as the loaf has been deposited on the carrier adapted to receive it, the feeding lever 29 of such loaf will then temporarily retreat so as not to contact with the loaf carriers, and to reappear again to receive another loaf from the platform 62, as previously mentioned. While the next 5 loaf is being carried over by the feeding drum, the loaf B³ will continue to descend in the embrace of its carrier as B⁴ until it has reached its position as B⁵, Fig. 12, which will bring the narrow space between 10 the face plates 13^b and 14^b directly opposite the knife 48, and if the machine is running continuously there will be another loaf—for instance, B⁶—immediately below. The 15 loaf carriers and loaf feeder will now be automatically halted long enough for the 20 knife to be advanced and sever the paper at the point previously named. The vertical portions 13^b and 14^b serving to support the vertical section of the paper against the inward pressure of the knife. The severed 25 section, designated as A², Figs. 1 and 11, can then be folded by special or any well known mechanism (not shown) before the loaf has reached the lower sprocket wheels 9 and 30 10, where the carriers will open as they pass around said wheels and allow a folded loaf to drop out. When the machine automatically starts again to repeat the operation just described, the free end of the paper will 35 be wrapped about the loaf B⁵ after the wrapper section A² has been severed. This will anchor such free end firmly while a loaf on the feeding drum is drawing the requisite amount of paper from the roll 59 40 to form its own wrapper. It will be understood that the paper strip is wide enough to form the end folds.

It will be noted that the endlessly movable double section loaf carriers are so constructed and journaled to their rods that they will open while passing around their rotatable supports, and remain rigidly parallel with each other intermediate thereof. For it is necessary that the carrier sections should open at the top to receive a loaf and at the bottom to discharge it and remain rigidly parallel between these points so as to retain the loaf while a wrapper is being severed and the folding completed.

In automatic machines adapted to wrap and fold articles of varying sizes, like, for instance, a loaf of bread, the first and most important step in the operation is to determine the length of wrapper for each individual loaf, and, when this can be done by the loaf itself, the folding operation is comparatively simple.

From the foregoing description it will readily be seen that each individual loaf 55 draws off from the reel paper sufficient to

cover its top and sides, while the length of the projecting flaps adapted to be folded against the bottom of the loaf are determined by the position of the knife for severing the wrapper section.

70

I do not wish to be confined to the exact details of construction and arrangement of the several mechanical elements shown to effect the object sought, as other suitable feeding and carrying mechanism can be employed whereby a loaf or other like article of irregular size is brought by feeding mechanism forcibly in contact with a paper strip to gather paper sufficient to cover the top and sides of a loaf and deposit the same 80 within the embrace of carriers and cut off a section of paper suitable to form the entire wrapper while the loaf is within the embrace of such carriers.

75

Having thus described my invention, what I claim is:

85

1. A bread-wrapping machine comprising a loaf feeder, an intermittently movable series of carriers to receive loaves from the feeder, means for supplying wrapping material between the feeder and the carriers to be laid across the outer surface of each loaf as it passes from the feeder to a carrier, and means for severing the wrapping material after each loaf, with a covering of 90 wrapping material, is transferred from the feeder to said carriers.

95

2. A bread-wrapping machine comprising a loaf feeder having means for supporting loaves projecting outwardly therefrom, an endless series of carriers to receive loaves from the feeder, means for supplying wrapping material between the feeder and the carriers to be laid across the outer surface of each loaf as it passes from the 100 feeder to a carrier, and means for severing the wrapping material after each loaf, with a covering of wrapping material, is transferred from the 105 feeder to said carriers.

105

3. In a wrapping machine of the character described, a series of intermittently and endlessly movable carriers, rotatable supports therefor having means for locating the carriers thereon, a loaf feeder adjacent to the carriers, said carriers adapted to automatically open while passing around their supports, said feeder adapted to force loaves of varying sizes in contact with a paper strip located between the feeder and carriers and draw off sufficient paper to envelop the top and sides of a loaf and deposit said wrapped loaf into one of the open carriers.

110

4. A wrapping machine of the character described comprising a series of intermittently and endlessly movable carriers, rods on which the carriers are pivotally supported, said supports having locating means thereon for the rods, said carriers adapted to open while passing around the supports 115 120 125 130

- 1 and remain rigidly parallel intermediate thereof, a loaf feeder adjacent to the carriers adapted to carry loaves of varying sizes and force a loaf against an interposed paper 5 strip and draw off paper sufficient to envelop the top and sides of each individual loaf and deposit said loaf on one of the open carriers, and means for automatically severing the paper.
- 10 5. A wrapping machine of the character described comprising carrier arms arranged to operate in pairs, each pair pivotally supported on a rod and having face plates at their free ends, intermittently rotatable 15 supports for the carrier arms, locating means on the supports for the rods, said arms adapted to open while passing around the supports and remain rigidly parallel intermediate thereof, a loaf feeder adjacent 20 to the carrier arms adapted to carry loaves of varying sizes and force a loaf against an interposed paper strip and draw off paper sufficient to envelop the top and sides of each individual loaf and deposit the loaf 25 within the open arms, and an automatically actuated knife adapted to pass between the face plates of the arms to sever the paper strip.
6. A bread-wrapping machine comprising 30 a loaf feeder, an endless series of carriers to receive loaves from the feeder, each of said carriers having two members, means being provided whereby said two members automatically open to receive a loaf and then 35 close upon it, means for supplying wrapping material between the feeder and the carrier to be laid across the outer surface of each loaf as it passes from the feeder to a carrier, and means for severing the wrapping material after each loaf, with a covering of wrapping material, is transferred from the feeder to said carriers.
7. In a wrapping machine of the character described, the combination with intermittently 45 movable loaf carriers, of an intermittently rotatable loaf feeder adapted to operate in unison with said carriers and in close proximity thereto, movable loaf supporting means on said feeder adapted to 50 force a loaf against a strip of paper located between the feeder and carriers to form a wrap for the top and sides of the loaf and deposit said wrapped loaf on a carrier and then temporarily disappear.
- 55 8. A bread-wrapping machine comprising a rotatable loaf feeder, an endless series of carriers to receive loaves from the
- feeder, means for supplying wrapping material between the feeder and the carriers to be laid across the outer surface of each loaf 60 as it passes from the feeder to a carrier, and means for severing the wrapping material at a point intermediate of two of the carriers after loaves have passed into such two carriers. 65
9. A wrapping machine of the character described comprising intermittently movable loaf carriers, an intermittently rotatable drum acting in unison with the carriers with a paper strip located between said carriers 70 and drum, movable loaf supporting feeders on said drum adapted to support a loaf and force the same against the paper strip to form a wrap sufficient to cover the top and sides of a loaf and deposit the same on one 75 of said carriers, means for temporarily causing said feeder to disappear for the purpose set forth. 80
10. A bread-wrapping machine comprising a loaf feeder having means for supporting loaves projecting outwardly therefrom, an endless series of carriers to receive loaves from the feeder, each of said carriers having two members one of which is provided with a spring retainer, means being provided whereby said two members automatically open to receive a loaf and then close upon it, means for supplying wrapping material between the feeder and the carriers to be laid across the outer surface of each loaf 90 as it passes from the feeder to a carrier, and means for severing the wrapping material after each loaf, with a covering of wrapping material, is transferred from the feeder to said carriers. 95
11. A bread-wrapping machine comprising a rotatable loaf feeder having means for supporting loaves projecting outwardly therefrom, said supporting means being movably mounted on the feeder, means for automatically projecting and retracting the supporting means during rotation of the feeder, an endless series of carriers to receive loaves from the feeder, and means for supplying wrapping material between the 100 feeder and the carriers to be laid across the outer surface of each loaf as it passes from the feeder to a carrier. 105

In testimony whereof I affix my signature in presence of two witnesses.
